CLAIM

The ornamental design for a water analysis instrument, as shown and described.

DESCRIPTION

FIG. 1 is a front perspective view of a water analysis instrument showing our new design;

FIG. 2 is a rear perspective view of the water analysis instrument of FIG. 1;

FIG. 3 shows a left perspective view of the water analysis instrument of FIG. 1;

FIG. 4 shows a front view of the water analysis instrument of FIG. 1;

FIG. 5 shows a left side view of the water analysis instrument of FIG. 1;

FIG. 6 shows a right side view of the water analysis instrument of FIG. 1;

FIG. 7 shows a top view of the water analysis instrument of FIG. 1;

FIG. 8 shows a bottom view of the water analysis instrument of FIG. 1; and,

FIG. 9 shows a back view of the water analysis instrument of FIG. 1.

In the drawings, the broken lines are for the purpose of illustrating environment only and form no part of the claimed design.
